US00D992735S

(12) **United States Design Patent** (10) **Patent No.:** **US D992,735 S**
(45) **Date of Patent:** **** Jul. 18, 2023**

(54) **SURGICAL INSTRUMENT**

(71) Applicant: **Iromed Group S.r.l.**, Rome (IT)

(72) Inventor: **Farhad Hafezi**, Baar (CH)

(73) Assignee: **IROMED GROUP S.R.L.**, Rome (IT)

(**) Term: **15 Years**

(21) Appl. No.: **29/752,920**

(22) Filed: **Sep. 29, 2020**

(30) **Foreign Application Priority Data**

Mar. 31, 2020 (EM) 007780549

(51) **LOC (14) Cl.** **24-02**

(52) **U.S. Cl.**
